CAN DUMP FOR ICE MACHINES

William Henry Aubrey, Waynesboro, Pa., assignor to Frick Company, Waynesboro, Pa., a corporation of Pennsylvania

Application December 2, 1932, Serial No. 645,473

11 Claims. (Cl. 62—113)

This invention relates to improved apparatus for removing ice from the cans in which it has been frozen. Heretofore it has been customary to immerse the ice cans in a bath of warm water to thaw the ice loose, then to withdraw the cans from the water, tilt them on a container to a sloping position and permit the ice to slide out. Sometimes the cans are tilted while the ice is still frozen in them and streams of warm water 5 are directed against the outside of the cans until the ice block is thawed loose and slides out.

An object of the invention is to remove ice from the container or can with a minimum amount of thawing to reduce the amount of ice 10 melted from the block.

A further object is to provide more sanitary means for removing ice from the cans, and further to prevent thawing water from entering into the storage room.

20 Further objects are to provide means for conserving space and water and to remove the ice from the cans more quickly than has been possible heretofore.

Referring to the accompanying drawings, 25 which are made a part hereof and on which similar reference characters indicate similar parts,

Figure 1 is a front elevation of the device,

Figure 2, a side elevation,

30 Figure 3, a plan view,

Figure 4, a diagrammatic view in side elevation showing the can in upright position,

Figure 5, a similar view showing the can in inverted position,

35 Figure 6, a similar view showing the can tilted for the ice block to slide out,

Figure 7, a detail view of an operating valve showing the valve in neutral position, and

40 Figure 8, a side elevation of a portion of a modified form of machine.

In the drawings 10 indicates a cradle which is supported upon journals 11 mounted in bearings 12 in suitable standards or supports 13. These standards may be secured upon a suitable foundation or frame 14 in any suitable way as by 45 bolts 15.

The cradle consists of a suitable frame work in which ice cans 42 may be supported and in which they are held by clamps 16 which may be hinged at 17 to a portion of the frame of the cradle and may be locked in closed position by latches 18. The frame is provided with guides 43 to hold the ice cans in place. The outer end of one of the shafts 11 carries a gear or pinion 19 which meshes with a rack 20, the 50 rack being held against the pinion by means of a

roller 21. A piston rod 22 connects the rack to a piston not shown operating in cylinder 23. Pressure fluid lines 24 and 25 deliver pressure fluid which may be water from a pipe 26 to operate the rack 20. Pressure fluid is controlled to the cylinder 23 by means of a manually operable valve 27. The construction of the valve is such that when the operating handle 28 is in one position such as that shown in Figure 7 the rack 20 will be locked in fixed position. When the handle is turned to the right as viewed in Figure 2, port 29 may then connect pipe 24 with exhaust pipe 30 and port 31 will connect inlet pipe 26 with pipe 25 to apply pressure to the lower end of the cylinder 23 to move the rack 20 upwardly. When the handle 26 is moved to the left to connect port 28 with pipe 24 through port 31, pressure will be applied to the top of the cylinder 23 and exhausted from the bottom to move the rack downwardly.

Means are applied also for automatically delivering warm water or steam against the sides of the can. This means comprises pipes 32 having perforations or spray nozzles 44 directed to spray fluid against the sides of the cans. A supply pipe is connected at 33 for supplying warm water or steam to the pipes 32. A flexible conduit 34 connects the pipe 33 with the pipes 32 and a valve 35 controls admission of warm fluid to the pipes 32. The valve 35 is normally held in a closed condition by a spring not shown but which may be of any well known construction. This valve has a stem 36 which is engageable by a cam 37 on the side of the cradle so that when the cradle is inverted the stem 36 is depressed by the cam to open the valve 35 to spray warm fluid against the sides of the ice cans.

A slide 38 is positioned beneath the cradle. This slide is arcuate in shape but the center of the arc is eccentric with respect to the center of the shaft 11. Beneath the slide 38 is an opening 39 for draining off the water used in thawing the ice from the sides of the cans.

In operation the cans in which the ice has been frozen are positioned within the cradle while the cradle is in the upright position shown in Figures 1 and 4. The cans are locked in position by means of the latch and clamps 16 and 18. The valve 27 is then manipulated to deliver pressure from line 26 through line 24 to the top of the cylinder 23. This rotates the cradle on its axis 11 inverting it into position shown in Figure 5 to invert the ice cans. When the ice cans have moved to the inverted vertical

55

position the cam 37 engages valve stem 36 to open the valve 35 and deliver warm fluid through the spray nozzles against the sides of the cans. The ice block as soon as it is thawed loose from the 5 walls of the can drops upon the slide 38. The valve lever 28 is then moved to deliver fluid from pressure line 26 to pressure line 25. This will move the rack 20 upwardly to rotate the cradle counterclockwise. As the cradle 10 approaches the position shown in Figure 6 the lower end of the block of ice will gradually slide out of the can following the curvature of the slide 38. The block of ice therefore is kept continually moving out of the can which prevents 15 it from freezing again to the sides of the can. When the edge of the block of ice has reached the upper end of the slide 38 the block then slides out upon a slide 49 from which it slides to a place of storage or is picked up.

20 It may be feasible to position the slide so that the block will slide by gravity out of the cans as soon as the blocks are thawed loose from the cans. Such possible construction is shown in Figure 8. Here the slide 41 is positioned beneath the cradle and has a downward slope so that the block of ice slides out practically as soon as it is thawed loose upon a slight movement of the cradle.

25 While a hydraulic motor and rack and pinion operative connection have been illustrated for tilting the cradle, I do not limit myself to this specific arrangement for accomplishing this purpose. The cradle might be tilted for example, by any suitable motor geared directly 30 to shaft 11 or might even be operated manually through a suitable train of gears.

35 By my arrangement the ice does not come in contact with the thawing water. Where the ice cans are immersed in tanks of warm water portions of the ice are exposed to this water. The water in these tanks soon becomes contaminated with salt and otherwise quite dirty. My arrangement prevents this, since only clean 40 warm water or steam is sprayed against the outside of the cans.

45 It will be obvious to those skilled in the art that various changes may be made in my device without departing from the spirit of the invention and therefore I do not limit myself to what 50 is shown in the drawings and described in the specification, but only as indicated by the appended claims.

Having thus fully described my said invention, what I claim as new and desire to secure by 55 Letters Patent, is:

60 1. A device for removing ice from the container in which it is frozen comprising a cradle, means for supporting the container in the cradle, a motor for inverting the cradle to invert the container, and means operated by the cradle for causing the application of thawing fluid to the outside of the container to thaw the ice loose from the container and permit it to drop by gravity from the container, substantially as set forth.

65 2. A device for removing ice from the containers in which it is frozen comprising a cradle, a motor for inverting the cradle, a plurality of conduits adapted to contain warm fluid for thawing the ice from the container side, a valve in control of said warm fluid, a cam on said container adapted to engage said valve to open it when the container is moved to an inverted 70 position, and means for tilting the cradle to per-

mit the ice to move by gravity from the container to the slide, substantially as set forth.

75 3. A device for removing ice from the containers in which it is frozen comprising a cradle, means for holding the container in the cradle, means for inverting the cradle to invert the containers, means for applying warm fluid to the container to thaw the ice from the sides of the container, an eccentric slide arranged so that as the cradle is returned from inverted toward upright position the ice will be caused to move by gravity gradually out of the container to prevent its freezing to the walls of the container, substantially as set forth.

10 4. A device for removing ice from containers in which it is frozen comprising means for inverting the container, a fluid motor for operating such means, a valve for operating such motor, a supply line for warm fluid, a valve in said line, and means for opening said valve 15 when the container is in inverted position to supply thawing fluid to the walls of the container, substantially as set forth.

15 5. A device of the kind described comprising a support for cans containing ice frozen therein, means for inverting said containers and for thawing the ice free from the sides thereof, a slide for receiving the ice, said support being positioned remotely from the ice storage whereby thawing water is prevented from spilling 20 into the ice storage, and means for limiting the removal of ice from the can to cause the block of ice to slide gradually from the can to the said slide substantially as set forth.

25 6. A device for removing ice from the cans in which it is frozen comprising a support for ice cans, a shaft carrying said support, said shaft having an operating wheel on one end, a motor operatively connected with said wheel, a valve in control of said motor, a plurality of 30 warm fluid conduits positioned adjacent said support, a valve in control of said warm fluid and a cam on said support engageable with said valve to apply warm fluid against the sides of the ice containers when the support has been 35 moved by the said motor to an inverted position, substantially as set forth.

40 7. A device for removing ice from the containers in which it is frozen comprising a support for said containers, a fluid motor for inverting 45 said support to invert the container, a plurality of conduits adapted to contain warm fluid for thawing ice from the sides of the container, a valve in control of said conduits, means on the container adapted to engage said valve to apply 50 warm fluid when the container has reached inverted position, and a slide positioned beneath the said support, said slide being arcuate and having the center of the arc eccentric with respect to the center of rotation of the support 55 whereby ice which is thawed from the walls of the container will be permitted to slide gradually out of the container as the container is moved from inverted back toward upright position, substantially as set forth.

60 8. A device for removing ice from the container in which it is frozen comprising a support for the container, means for inverting the support, means for supplying thawing fluid to the walls of the container to thaw the ice loose 65 from the walls, a valve for controlling said fluid, and a cam on said support adapted to open said valve only when said container is inverted approximately to a vertical position.

65 9. A device for removing ice from the con-

tainer in which it is frozen comprising means for inverting the container, means for supplying thawing fluid to the walls of the container, said last-mentioned means including spray nozzles directed against a side of the container and mounted to move with the container, a valve controlling the supply of thawing fluid and means operatively associated with the means for inverting the container for opening said valve when the container is in an inverted position.

10. A device for removing ice from the container in which it is frozen comprising means for inverting the container, means for supplying thawing fluid to the walls of the container, an arcuate slide to receive the block of ice from the inverted container and arranged to permit the ice to slide gradually out of the container

as the container is returned from the inverted position, and means to control the supply of thawing fluid in accordance with the position of the container.

11. A device for removing ice from the container in which it is frozen comprising means for inverting the container, means for supplying thawing fluid to the walls of the container, an arcuate slide to receive the block of ice from the inverted container and arranged to permit the ice to slide gradually out of the container as the container is returned from the inverted position, said arcuate slide having elevated sides to collect the thawing fluid, and a drain from the bottom of said slide.
